UNITED STATES PATENT OFFICE.

OTIS M. KIRLIN, OF WATERTOWN, SOUTH DAKOTA.

SCALE.

Application filed March 13, 1922. Serial No. 543,204.

To all whom it may concern:

Be it known that I, OTIS M. KIRLIN, a citizen of the United States, residing at Watertown, in the county of Codington and State of South Dakota, have invented 5 certain new and useful Improvements in Scales; and I do hereby declare the following to be a full, clear, and exact description of the invention, such as will enable 10 others skilled in the art to which it appertains to make and use the same.

My present invention relates to improvements in scales and, more particularly, to scales of the type disclosed and claimed in 15 my two U. S. Letters Patents, 1,184,103 issued May 23, 1916 and 1,282,859 issued October 29, 1918, and has for its object to improve the same in the several particulars hereinafter noted.

20 To the above end, the invention consists of the novel devices and combinations of devices hereinafter described and defined in the claims.

25 In the accompanying drawings, which illustrate the invention, like characters indicate like parts throughout the several views.

Referring to the drawings:

Fig. 1 is a front elevation of an improved scale;

30 Fig. 2 is a view partly in side elevation and partly in central vertical section taken on the line 2—2 of Fig. 1;

35 Fig. 3 is a fragmentary view partly in elevation and partly in vertical section taken on the line 3—3 of Fig. 2;

Fig. 4 is a fragmentary front elevation with some parts sectioned on the line 4—4 of Fig. 2;

40 Fig. 5 is a detail view partly in plan and partly in horizontal section taken on the line 5—5 of Fig. 4;

Fig. 6 is a fragmentary view in diagram with a portion of the casing sectioned in the vicinity of the line 6—6 of Fig. 2;

45 Fig. 7 is a detail view principally in section taken on the line 7—7 of Fig. 6; and

Fig. 8 is a view in diagram showing the lamp circuit.

50 The numeral 10 indicates a hollow base over a portion of which is located a scale platform 11 supported on a lever 12 in the customary or any suitable manner. A casing 13 is supported on the base 10 at one side of the platform 11 and is provided 55 with a face plate 14 and a back plate 15.

Formed in the face plate 14 is a perpendicular slot which affords a sight opening 16 and which sight opening, at its upper extremity, is widened to increase the field of said opening.

60 A tare or main beam 17 has intermediately secured thereto a knife bearing 18 which projects from opposite sides thereof and is fulcrumed in apertures in the prongs of a depending bearing 19 secured to the

casing 13. The short or left-hand portion of the tare beam 17 is connected to the lever 12 by a long link 20 which works through an aperture in the top of the base 10. A

sliding poise 21 is mounted on the long 70 end portion of the tare beam 17 and its extreme movements on said beam are limited by stops 22 and 23. Formed in the

upper edge of the tare beam 17 are a plurality of, as shown three, transverse V-shaped notches 24, any one of which may be engaged by a correspondingly formed detent 25 on the poise 21. When the poise 75

21 is in engagement with the stop 22, said poise is at zero and its detent 25 is in engagement with the left-hand notch 24. The

other two notches 24 are spaced and indicate 20 and 40 pounds, respectively. When the poise 21 is moved to its extreme right- 80

hand position, the detent 25 is in engagement with the stop 23 and increases the 85 weighing capacity of the scale to 60 pounds.

To shift the poise 21 on the tare beam 17, there is provided an operating lever 26 which underlies said beam in the plane

thereof, and extends through an intermediate slot 27 in the poise 21 for the tare beam 17. The operating lever 26 is intermediately fulcrumed at 28 to the poise 21, and its left-hand or short end is provided 90

with an upwardly projecting detent 29 arranged to enter any one of the plurality of lock notches 30 formed in the lower edge of the tare beam 17 and longitudinally 95

spaced the same distance apart as the 100 notches 24.

The long or right-hand end of the operating lever 26 extends through a vertical slot 31 in the casing 13 and terminates in 105 a ball-like hand-piece 32. The initial lifting pivotal movement of the hand-piece 32

will disengage the detent 29 from the lock notch 30 with which it is interlocked and a further upward movement of the hand-piece 32 will cause the operating lever 26 to en- 110

gage the lower end of the slot 27, as a stop 33. A still further lifting movement of the hand piece will cause the operating lever 26 and the poise 21 to move together and thereby rock said poise on the tare beam 17 and lift its detent 25 out of the engaged notch 24. While the poise 21 is thus held by the operating lever 26, the same may be shifted by a sliding movement to any desired point on the tare beam 17 by an endwise movement of the operating lever 26. As soon as the hand-piece 32 is released, the detent 25 will enter the notch 24 over which it is positioned, and the detent 29 will enter the overlying notch 30. Marked on the operating lever 26 are the numerals 20, 40 and 60, spaced the same distance apart as the notches 24 and 30, and as the operating lever 26 is moved endwise out of the slot 31, to shift the poise 21 and thereby increase the weighing capacity of the scale 20, 40 or 60 pounds, said numerals will successively appear and thus permit the operator to properly position the poise 21 on the tare beam 17 and permit the detent 25 to enter any one of the notches 24. It is, of course, understood that the notches 24 may be spaced to vary the weighing capacity any desired number of pounds.

Secured to the tare beam 17 for common oscillatory movement therewith, is an auxiliary scale beam 34 which works outside of the casing 13 and is graduated from zero to 10 to indicate pounds and fractions thereof.

Slidably mounted on the beam 34 is a poise 35 having a thumb screw 36 for engagement with said beam to hold the poise where set and the extreme sliding movement of the poise 35 on the beam 34 is limited by stops 37. At the zero end of the beam 34 is a screw-threaded stem 38 on which is mounted a knurled weight 39 for balancing the scale. As one means of securing the beam 34 to the beam 17, there is rigidly secured to the inner face of said beam 34 a laterally projecting stud 40 rigidly secured by a set screw 42 to an offset bracket 43 rigidly secured to the tare beam 17. The stud 40 is axially aligned with the knife bearing 18, and extended through an aperture 41 in the casing 13.

Extending axially through the face plate 14 is a horizontal dial shaft 44 loosely journaled on the peripheries of pairs of overlapping bearing wheels 45. The dial shaft 44 is further journaled on set screws 46 which have conical engagement therewith. An indicator dial 47 is mounted on the dial shaft 44 for rotation therewith within the casing 13 close to the face plate 14. This indicator dial 47 is graduated to indicate pounds and fractions thereof and value amounts in substantially the same arrangement as in my patent issued May 23, 1916 heretofore identified. The weighing grad-

uations are visible through the expanded portions of the sight opening 16.

In actual construction, the sight opening 16 will be covered by a transparent panel, and a hair line, preferably colored, will be 70 extended through the vertical center of this panel and with which the zero point of the dial 47 registers when in normal position. On the vertical edge portions of the face plate 14, at the sight opening 16, are indicated, prices in cents per pound. The weight graduations and computed amounts upon the rotating dial 47 are visible through the sight opening 16 and are to be read on the hair line, and said computed amounts 80 coincide with the price amounts marked on the face plate 14 on either side of said opening.

The shaft 44, and hence the dial 47, is oscillated by the lever 12 by a pair of flexible connections, as shown, in the form of steel tapes 48, the inner ends of which are reversely wound upon a drum 49 and secured thereto. This drum 49 is keyed to the shaft 44 for rotation therewith. The outer ends of the tapes 48 are extended vertically in opposite directions and secured to a vertically extended bar 50 located at one side of the drum 49. To vary the tension of the tapes 48, the upper one is connected to the bar 50 by an adjustable block 51.

To the lower end of the bar 50 is rigidly secured a horizontal cross head 52, from the ends of which is suspended a pair of depending links 53 which work through apertures in the top of the base 10 and support a horizontal cross head 54, to the intermediate portion of which is pivoted the lever 12.

To give a steady action to the movable parts of the scale and to eliminate vibration of the dial 47, there is provided a retarding device comprising a cylindrical receptacle 55 partly filled with liquid α preferably mercury, which normally bears upon its surface, a float 56 having a stem 57 secured to the under side of the cross head 52. This receptacle 55 is suspended from the casing 13 by an annular bracket 58 through which said receptacle extends and is supported thereon by an annular bead or flange 59 formed with said receptacle. It is highly important to note that the support for the receptacle 55 is located substantially at the 120 normal surface of the liquid α when the scale dial 47 is at zero. The purpose of thus mounting the receptacle 55 is that any change of temperature which tends to lengthen or shorten the receptacle 55 and the liquid column α will not change the normal level of the surface of the liquid α relative to the scale body.

It will be noted that the float 56 is in the form of a vertically disposed tube having 120

an open top and closed bottom, and it is important to note that the stem 57 extends axially into the float 56 and is secured to the bottom thereof. The object of thus attaching the stem 57 to the bottom of the float 56 is that any temperature change tending to lengthen or shorten the float will not change the position of its lower end to the body of the scale or surface level of the liquid z .

Under the weighing movement of the scale beam 12 the float 56 will be forced into the liquid z and to restrict the rate of movement of the liquid z , displaced by the float 56, there is formed on the inner wall of the receptacle 55, an annular flange 60 located substantially at the normal surface of the liquid z . Obviously, this flange 60 forms a restricted passageway through which the float 56 moves vertically and the displaced liquid z is forced upward through this restricted passageway. To prevent the liquid z from spilling out of the receptacle 55, in case the scale is turned onto its side, I provide a cover 61 for said receptacle with a depending contracted sleeve 62 through which the float stem 57 works. The term float is herein used in a broad sense to cover a plunger or the like.

To slightly vary the altitude of the liquid z of the receptacle 55, there is mounted in the rear wall of said receptacle, below the flange 60, a relatively large screw plug 63 adapted to be projected into or withdrawn from the liquid z and thereby raise or lower the level thereof, as the case may be. This screw plug 63 may be turned by a screw driver inserted through an aperture in the rear wall of the casing 13.

To dampen or check the too rapid movement or oscillation of the dial 47, there is provided a plurality of circumferentially spaced permanent magnets 65 secured to the casing 13 and between the poles of which said dial is free to rotate without coming into contact therewith. The dial 47 is preferably made of aluminum and the permanent magnets 65 have no effect thereupon, other than that the rotation thereof is retarded by the resistance of the permanent magnets to the movement of the metallic dial between their poles and which resistance increases with the increased speed of the movement of the dial 47.

Referring now to Fig. 8 of the drawings there is diametrically illustrated means for automatically illuminating the scale during the weighing action, and which means includes a normally open circuit comprising a battery 66, lead wires 67, a light bulb 68 and the liquid z . The two leading wires 67 are attached, the one to a lower terminal 69 and the other to an upper terminal 70. These terminals are secured to the receptacle 55 and extend into the interior thereof, but

are insulated therefrom. The lower terminal 69 is located near the bottom of the receptacle 55 and its inner end is always in the liquid z . The other or upper terminal 70 is located above the rib 60 and, when the scale is at zero, the level of the liquid z is below the same. During the initial weighing action of the scale, the liquid z , which as previously stated is mercury, is displaced by the float 56 and as the same rises in the receptacle 55, comes in contact with the contact 70 and thereby completes the circuit between the lead wires 67. The light bulb 68 may be located at any desired point on the scale and it is not thought necessary to illustrate the same other than as shown in Fig. 8.

As soon as the weight on the scale is removed, the liquid z will recede, during the lifting movement of the float 56, and break the circuit between the contacts 69 and 70.

What I claim is:

1. The combination with a scale casing, of a main scale beam in the casing fulcrumed for oscillatory movement, an auxiliary scale beam outside of the casing and secured for common oscillatory movement with the main scale beam, a poise on each of said scale beams, and means for operating the poise on the main scale beam.

2. The combination with a scale casing, of a main scale beam in the casing fulcrumed for oscillatory movement, an auxiliary scale beam outside of the casing, means connecting the auxiliary scale beam to the main scale beam for common oscillatory movement therewith, said means being extended through the casing substantially at the axis of the fulcrum for the main scale beam, a poise on each of the scale beams, and means for operating the poise on the main scale beam.

3. The structure defined in claim 1 in further combination with means for moving the poise on the main scale beam from the outside of the casing.

4. The structure defined in claim 3 in which the means for moving the poise on the main scale beam is provided with characters indicating the position of the poise on the main scale beam.

5. The structure defined in claim 1 in further combination with a balancing device on the auxiliary scale beam.

6. The combination with a scale beam, of a poise on the scale beam and having interlocking engagement therewith at predetermined points, and means for sliding the poise on the scale beam, said means being arranged to interlock with the scale beam at predetermined points.

7. The combination with a scale beam having lock notches, of a sliding poise on the scale beam and having interlocking engagement therewith at predetermined points, of

an operating lever intermediately pivoted to the poise and having a detent arranged to enter the lock notches into the scale beam.

8. The structure defined in claim 7 in which the operating lever is arranged to move under the action of gravity to engage its detent with the lock notches in the scale beam.

9. The combination with a casing, of a scale beam mounted in the casing and having lock notches, a sliding poise on the scale beam, of an operating lever for the poise arranged to work in an aperture in the casing, said operating lever having a detent arranged to enter the lock notches of the scale beam and also having identifying characters for indicating the position of the poise on the scale beam.

10. The combination with a casing, of a scale beam mounted in the casing and having lock notches, a sliding poise on the scale beam, of an operating lever for the poise arranged to work in an aperture in the casing, and a detent for co-operation with the lock notches to position the poise on the scale beam, said operating lever having identifying characters for indicating the position of the poise on the scale beam.

11. The combination with a scale beam having two sets of lock notches, a sliding poise on the scale having a detent arranged to enter the lock notches of one set, and an operating lever intermediately pivoted to the poise and having a lock detent arranged to enter the lock notches of the other set.

12. The structure defined in claim 11 in which the operating lever may be moved to disengage the detent on the sliding poise from the respective lock notch when its detent is disengaged for the respective lock notch.

13. The structure defined in claim 11 in which the operating lever may be moved to carry said detents out of the engaged lock notches to permit the sliding movement of the poise on the scale beam.

14. The structure defined in claim 11 in which the pivotal movement of the operating lever is limited whereby the poise may be lifted to disengage its detent from the engaged lock notch.

15. The combination with a movable scale indicator, of a retarding device for the indicator comprising a liquid containing receptacle, a float, and a scale-actuated connection for forcing the float variably into the liquid under the weighing movement of the scale, said connection being attached to the float substantially at the normal level of the liquid.

16. The combination with a movable scale indicator, of a retarding device for the indicator comprising a liquid containing receptacle, a tubular float having a closed bottom, and a scale-actuated stem attached to

the lower end of the float for forcing the float variably into the liquid under the weighing movement of the scale.

17. The combination with a movable scale indicator, of a retarding device for the indicator comprising a liquid containing receptacle, a tubular float having a closed bottom, and a scale-actuated stem extending into the float and attached to the lower end of the float for forcing the float variably into the liquid under the weighing movement of the scale.

18. The combination with a movable scale indicator, of a retarding device for the indicator comprising a suspended liquid containing receptacle, a float arranged to be forced variably into the liquid under the weighing movement of the scale, said receptacle being supported substantially at the normal level of the liquid in its suspended position.

19. The combination with a movable scale indicator, of a retarding device for the indicator comprising a suspended liquid containing receptacle, a float arranged to be forced variably into the liquid under the weighing movement of the scale, said connection being attached to the float at substantially the normal level of the liquid, said receptacle being supported substantially at the normal level of the liquid in the receptacle in its suspended position.

20. The combination with a movable scale indicator, of a retarding device for the indicator comprising a liquid containing receptacle, a float arranged to be forced variably into the liquid under the weighing movement of the scale, and a bracket, at substantially the normal level of the liquid, on which the receptacle is supported in an elevated position.

21. The combination with a movable scale indicator, of a retarding device for the indicator comprising a liquid containing receptacle, a float arranged to be forced variably into the liquid under the weighing movement of the scale, and a bracket, said receptacle having a shoulder, at substantially the normal level of the liquid, for engagement with the bracket to support the receptacle in an elevated position.

22. The combination with a movable scale indicator, of a retarding device for the indicator comprising a liquid containing receptacle, a float arranged to be forced variably into the liquid under the weighing movement of the scale, a normally opened battery circuit including a light bulb and two terminals, and means for making and breaking the circuit between said terminals by the movement of the float into the liquid under the weighing action of the scale to switch on and off the light bulb.

23. The combination with a movable scale indicator, of a retarding device for the indi-

- cator comprising a liquid containing receptacle, a float arranged to be forced variably into the liquid under the weighing movement of the scale, and a normally opened 5 battery circuit including a light bulb, two terminals and the liquid in the receptacle, one of said terminals always being in said liquid and the other being above the normal level of the liquid but arranged to be engaged by the liquid when displaced by the 10 float during the weighing movement of the scale to switch on and off the light bulb.
24. The combination with an oscillating
- metallic circular scale indicator, of a permanent magnet located at the circumference of 15 said indicator, said indicator being arranged to oscillate between the poles of the permanent magnet.
25. The combination with an oscillating metallic circular scale indicator, of a plurality of circumferentially spaced permanent 20 magnets located at the circumference of said indicator, said indicator being arranged to oscillate between the poles of the magnets.

In testimony whereof I affix my signature.
OTIS M. KIRLIN.
